UNITED STATES PATENT OFFICE.

JOHN F. NEWSOM, OF PALO ALTO, CALIFORNIA.

SOUND MUFFLER.

Application filed April 21, 1925. Serial No. 24,863.

The invention relates to means for minimizing or reducing the volume of sound entering a room or apartment through a ventilating opening.

5 An object of the invention is to provide means for intercepting the sound waves traveling toward or through the ventilating opening to reduce the sound disturbance in the room.

10 Another object of the invention is to provide a sound muffler constructed either to reflect or absorb sound waves directed toward or through the opening, or to both reflect and absorb the sound waves either before or after they have passed through the opening, to minimize the sound disturbance within the room.

15 Another object of the invention is to provide a simple sound intercepting device for use in connection with a window arranged in an opening in a thick wall.

20 Another object of the invention is to provide a window with a sound intercepting device which does not present an unsightly 25 appearance on the exterior or interior of the building.

25 The invention possesses other advantageous features, some of which with the foregoing will be set forth at length in the following description where I shall outline in full that form of the invention which I have selected for illustration in the drawings accompanying and forming part of the present specification. In said drawings I 30 have shown several forms of devices embodying my invention, but it is to be understood that I do not limit myself to such forms since the invention, as set forth in the claims, may be embodied in a plurality 35 of other forms.

40 The roar of sound from the street which enters the open windows of office buildings, hotels, hospitals and homes is very annoying and it is an object of the present invention to intercept the sound waves which ordinarily enter the room through open windows and thus reduce or minimize the annoyance. These sounds emanate principally 45 from certain sources in the street, such as street car tracks and crossings and moving street cars and automobile horns, and the device of my invention is arranged to intercept the direct sound waves from these sources, and also to intercept reflected sound

waves which are directed toward the opening in the window. Noises also enter rooms through open transoms and other openings provided for establishing ventilation. By eliminating or reducing the intensity of these sound waves, the volume of sound entering the room is very greatly reduced and the annoying effect of the loud and harsh sounds is practically eliminated.

Efforts made in the past to minimize the effect of outside noises which enter rooms have consisted of reflectors arranged to place the window opening in the sound shadow or of sound absorbents in the room placed on the ceilings and walls thereof, to absorb the sound energy after it has passed into and spread through the room; whereas in my invention I deal with and nullify the objectional effects of the entering sound while the sound energy is in immediate proximity to the window opening, in its most confined space and where in consequence devices for nullifying its effect can be most efficiently brought to bear upon it.

45 In accordance with my invention, I arrange sound muffling or nullifying means adjacent the opening, so that the sound waves are acted upon while they are confined to a small area. These devices comprise a sound shield on the outside of the opening or window to intercept sound traveling toward the opening and devices within the room adjacent the opening to either absorb or reflect back through the opening, or both absorb and reflect back sound waves which pass through the opening. These 50 absorbing or reflecting devices are arranged within the room adjacent the opening, so that they are in the path of the waves passing through the confined space of the opening, so that a large portion of the sound which passes through the opening is either reflected back through the opening or absorbed or both. These devices are spaced away from the opening a sufficient distance to permit of ventilation and are so arranged 55 as to minimize the amount of sound which enters the room.

Several forms of devices for accomplishing this result are shown in the accompanying drawings in which:

60 Figure 1 is a sectional perspective view of a window open at the top and bottom and provided at the top with means for

deadening and reflecting back the sound waves which pass through the upper opening and provided at the bottom with a sound shield which is interposed between the opening and the source of sound.

Figure 2 is a sectional perspective view of an open window, the lower opening being provided with a sound shield positioned to place the lower opening in the sound shadow and in which the upper opening is provided with a sound shield for placing it in the sound shadow, with sound deadening and reflecting means for further reducing the volume of sound directed toward the opening and with sound deadening and reflecting means arranged within the room adjacent to the opening and with a reflecting device for reflecting back any sound waves which pass the latter deadening and reflecting device.

Figure 3 is a sectional perspective view of an open window provided with devices of my invention, the lower opening being provided with means for placing the opening in the sound shadow and the upper opening being provided with means for placing the opening in the sound shadow, for absorbing sound waves which strike the lower side of the upper surface of the opening and with means arranged within the room adjacent to the opening for deadening and reflecting back through the opening sound waves which enter through the opening.

Figure 4 is a sectional perspective view of an open window showing the lower opening provided with means for placing the opening in the sound shadow and with means for reflecting back sound which passes through the opening, and the upper opening provided with means for deadening and reflecting back through the opening sound waves which enter through the opening, in combination with a reflector for reflecting back through the opening sound waves which pass by the deadening and reflecting device.

Figure 5 is a sectional perspective view of an open window, showing the lower opening provided with means within the room for reflecting back through the opening sound waves which enter through the opening and showing the upper opening provided with means for reflecting back and absorbing sound waves which are directed toward the under surface of the upper side of the opening and with means within the room for receiving and absorbing the sound waves which pass through the opening.

Figure 6 is a sectional perspective view of an open window, showing the lower opening provided with means for placing the opening in the sound shadow and showing the upper opening provided with means for placing such opening in the sound shadow, together with means for absorbing and reflecting back through the openings, sound waves which enter through the openings.

This type of construction is particularly advantageous in windows in the higher stories of office buildings.

Figure 7 is a sectional perspective view of the upper portion of a window opening, showing a sound absorbing and reflecting device arranged within the room.

The device of my invention is constructed to reduce to a minimum the amount of sound entering a room through a window opened to provide ventilation. This is accomplished by a combination of sound interceptors which first reduce the amount of sound passing through the opening and then intercept the reduced volume of sound which has passed through the opening at a point adjacent to the opening, and thus prevent this sound from entering the room. The device for accomplishing this result may be arranged in various combinations, and in the various figures of the drawings I have shown various combinations which cooperate in different ways to produce the desired result. In each of the figures I have shown the device in association with an open window, arranged in a thick wall 2, but it is to be understood that the invention is not limited to use in connection with windows set in thick walls. The window frame 3 is preferably set in the opening in a plane spaced inward from the outer surface of the wall, so that the movable sashes 4 and 5 are spaced inward from the outer surface of the wall 2. The opening in the wall is provided with a sill or bottom surface 6, with a top surface 7, and with side walls 8. The various figures of the drawings are perspective views taken from a point outside the window. Since, for optimum ventilation, it is desirable to open the window both at the top and the bottom, I have shown the devices of my invention in cooperation with the top and bottom openings, but it is to be understood that I do not limit myself to sound muffling devices associated with both the top and the bottom openings since devices associated with one opening only may be employed when desirable.

In the construction shown in Figure 1, the lower opening in the window is placed in the sound shadow by a sound intercepting plate 12, which is positioned between the opening and the source of sound. This plate 12 may consist of a plate of glass, arranged within the opening in the wall and extending across the opening from side wall to side wall and preferably resting against the bottom wall 6. The side walls of the opening in the wall prevent sound traveling longitudinally along the street from entering the window opening, but when the wall is not sufficiently thick to permit the sound intercepting plate to be arranged in the window opening, side walls such as shown in the Parker Patent No. 1,108,613 may be

used. The plate 12 is preferably mounted in guides or supports 13, the space between the plate and the support being filled with rubber or other conformable material, to dampen any vibrations which may be set up in the plate 12. The supports 13 are preferably hinged or pivoted at their lower ends so that the plate 12 may be adjusted to any desired angle and so that the plate may be folded to inoperative position when desired. The plate 12 may intercept and collect rain and for that reason is provided along its lower edge with vents 12' to discharge the collected water. The under surface of the upper side 7 of the opening in the wall, on one or both sides of the frame 3, is covered with a sound deadening or absorbing material 14, such as felt or sponge rubber, so that a portion of the sound striking this surface at an angle will be absorbed and not reflected through the opening into the room. The sound absorbent may consist of any well known sound absorbent such as hair felt or mineral wool, but I prefer soft sponge rubber on account of its resistance to moisture, the ease with which it can be attached and the fact that it can be produced in any desired color to harmonize with surrounding objects. The sound absorbing material 14 at the top of the opening is preferably protected from rain by the drip plate 9, projecting outward from the wall. Arranged within the room adjacent the window opening and extending across the opening at the top thereof is a sound shield comprising a plate 15, preferably formed of metal, covered with a sound deadening or absorbing material 16, which will cause the amount of sound distributed into the room to be greatly reduced. The major portion of the sound which passes by the interceptor 15 is directed downward, substantially vertically, and this sound is reflected outward through the bottom opening in the window by the reflector plate 17 extending across the opening in the wall adjacent the lower opening of the window and inclined to reflect outward any vertical or substantially vertical sound waves striking it.

In the construction shown in Figure 2, the arrangement of the elements at the lower opening of the window is substantially the same as that shown in Figure 1, with the exception that the reflector 18 which is arranged within the room adjacent the lower opening, is substantially vertical, so that it will reflect outward sounds which enter through the opening at the lower part of the window. In this construction, a sound interceptor or sound shield 21, preferably comprising a curved sheet of glass extending across the opening in the wall, is arranged between the upper opening in the window and the source of sound, to reflect

backward toward the source of sound, sound waves which are traveling toward the opening in the window. This shield 21 is spaced downward from the upper surface 7 of the opening to provide for ample ventilation. The upper surface 7, in addition to being provided with sheets of sound absorbing material 22, similar to the sheet 14 disclosed in Figure 1, is provided with one or more curved sound reflecting vanes 23 which reflect backward sound waves which are traveling toward the upper surface 7 of the window opening. Since the line of direction of sound from the source lies at a different angle for different altitudes of the window, the shield 21 is pivotally mounted and is adjustable about its pivot, so that it may be moved to lie between the opening at the top of the window and the source of sound. Arranged within the room adjacent the top window opening and spaced inward therefrom is a sound shield 24, preferably comprising a metallic plate covered with a sound deadening or absorbing material and this plate preferably is curved inward toward the window sash at its lower edge to reflect backward through the window opening sound which enters through the opening. The reflector 24 is shown extended past the plane of section to show the end or side wall 24' which acts to prevent the lateral travel of sound into the room and such end walls are preferably provided on all of the reflecting and absorbing devices shown in the drawings to prevent lateral dispersion of the sound. When desirable, the pocket or recess formed by the reflector or absorber may be covered at its open side with a thin cloth or screen or other fabric to keep dust and insects and birds from the insides of the recesses. Sound will pass the shield 24 and move downward into the room and a curved reflector 25 is arranged adjacent the window sash below the shield 24 to reflect backward into the opening in the window, the major portion of the sound which passes by the interceptor 24. The reflector 25 is curved so that the reflected sound from all points thereof is directed toward the upper window opening.

The construction shown in Figure 3 is a modification of that shown in Figure 2, in which the outside shield 26, guarding the lower opening in the window, is arranged substantially vertical. Since sound waves usually emanate from a source in the street, which is at a lower level than the windows, the vertical shield 26 will place the lower window opening in the sound shadow and reflect away from the window the sounds which strike the shield. The upper opening in the window is shielded by the inclined shield 27 which places the upper opening in the sound shadow. Some sound may be reflected from the shield 27 substantially ver-

- 4
- tically toward the sill 6 and to prevent such sound entering through the lower window opening, the sill is covered with a layer 28 of sound absorbing material such as felt or 5 rubber sponge. The upper surface of the opening in the wall is covered with a sheet 29 of sound deadening material to minimize the amount of reflected sound which will pass through the upper window opening.
- 10 Arranged within the room and spaced from the sash and positioned adjacent the upper window opening is a sound trap or sound deadening device which will absorb a large proportion of the sound entering through 15 the top window opening. This sound deadening device comprises a plurality of curved vanes 31 extending across the window opening and covered with a sound deadening material. The sound is trapped between the 20 vanes and its energy is spent, so that substantially all of the sound is absorbed. The vanes gradually approach each other as they progress inwardly, providing troughs of decreasing depth into which the sound waves 25 travel. These troughs are preferably divided into a plurality of pockets by the vertically spaced walls 30, which are also covered with sound deadening material. The sound is trapped in the pockets and the un- 30 absorbed portions rebound from the surface of the deadening material to again strike deadening material. The pockets decrease in size rearwardly, so that in effect the sound waves are led into and absorbed in a 35 funnel lined with sound absorbing material. The sound waves may rebound a plurality of times but become weaker at each rebound, so that substantially all of the sound is absorbed.
- 40 The construction shown in Figure 4 is provided with an arrangement at the bottom window opening substantially the same as that shown in Figure 2, with the exception that the inside reflector 32 at the bottom 45 window opening is curved toward the sash at its upper end to reflect downward through the bottom window opening sound which enters through the lower window opening. The reflector 32 is preferably arranged in a 50 pocket 32^a into which it may be lowered when desired, any suitable type of raising device being used for that purpose. A suitable form of device may be constructed along the lines of the devices 55 now used for raising and lowering automobile windows. In this construction also the exterior sound shield is omitted at the top window opening and the sound which enters through such opening is deadened 60 by the sound trap 33 extending across the opening in the wall at the top thereof and spaced from the window. This trap comprises a box-like structure having a front wall formed of a plurality of wedges 65 34^a of a sound deadening material, which form between them a plurality of funnels 34^b, open at their ends. The back of the box is lined with a layer 34^c of sound deadening material which is spaced away from the bottoms of the funnels to form an ex- 70 pansion chamber for the sound which passes through the funnels and such sound is substantially entirely absorbed in said chamber. The sound is largely deadened by contact with the walls of the funnels and the 75 remaining sound is deadened in the expansion chamber. Since this structure employs no outside sound interceptor, the amount of sound which will pass downward between the absorber 33 and the window will be 80 greater than that which will pass by the absorber shown in Figure 3 and, to prevent this sound from entering the room, a curved reflector 35 is arranged adjacent the sash to reflect upward and outward through the 85 window opening sound which passes the absorber 33 and strikes the reflector 35. The reflector 35 is pivoted at its lower edge so that it may be swung to adjusted positions or so that it may be swung upward 90 against the sash when its use is not desirable.
- 95 In the structure shown in Figure 5 the lower window opening is protected by an inside sound reflecting plate 36 which is inclined to reflect outwardly through the bottom window opening sounds which enter through such opening and which is preferably hinged so that it may be moved to adjusted or inoperative positions. As in the construction shown in the prior figures, this plate 36 is preferably formed of glass and is set in a conformable material such as rubber, so that any vibrations which may be induced therein are deadened. At the upper 100 window opening, curved reflectors 37 are arranged to reflect backwardly sound waves which are directed toward the upper surface 7 of the opening. These sound waves are further deadened by a strip of sound 105 absorbing material 38 arranged at the bases of the vanes 37. Arranged within the room adjacent the upper window opening and extending across the opening in the wall and spaced backward from the window frame 3 110 is a sound absorbing device comprising a plurality of curved plates 41 of decreasing distance apart backwardly, so that funnel shaped passages are provided between the 115 plates. The sound enters these funnel shaped passages or horns and is conducted to the small or discharge end thereof where it is discharged into a box 42 containing a 120 sound absorbing or deadening material 43.
- 125 In the construction shown in Figure 6, the arrangement at the bottom of the window is the same as in Figure 4. At the top of the window, however, the top window opening is placed in the sound shadow by the substantially horizontal plate or shield 130

45, which extends across the opening in the wall. Sound striking the under surface of the shield 45 is reflected downwardly against the reflector 46, extending across the opening 5 in the wall and is reflected outwardly by the reflector 46 so that it may not pass downwardly toward the reflector 12 at the bottom window opening. The sound which enters through the top window opening is trapped 10 by the plurality of vanes 47 extending across the opening in the wall behind the top window opening. These vanes 47 are curved downwardly and approach each other at the back plate 48, and the vanes and the back 15 plate are covered with sound absorbing material, to absorb a large portion of the sound. The vanes 47 are so formed and positioned that any sound which discharges from the pockets between the vanes is directed 20 toward the window opening, so that the unabsorbed sound is discharged outward through the window opening. The sound which passes downward in the space between the window pane and the vanes 47 25 is largely reflected backward by the reflector 49, which is curved so that the reflected sound is directed through the window opening.

In Figure 7 I have shown a modified form 30 of the sound absorbing and reflecting device which is arranged within the room adjacent the top window opening. This device consists of a back plate 51 provided with a plurality of downwardly curved spaced vanes 35 52 covered with a sound absorbing material. The sound striking these vanes is reflected back and forth in the chambers between the vanes and is thus deadened. The plate 51 is preferably hinged at its upper edge so that the angle of the structure may be varied or so that it may be moved upward out of the way when desired. This device may be used in conjunction with the reflector 49 shown in Figure 6, so that unabsorbed sound, 45 striking the reflector 49 will be directed out through the window opening.

I claim:

1. The combination with a wall having an 50 opening to provide ventilation in a contiguous room of a sound absorbing device arranged outside the opening to absorb a portion of the sound which is directed toward the opening, and a sound reflector arranged within the room adjacent the opening to reflect a portion of entering sound backward through the opening.

2. The combination with a wall having an 55 opening to provide ventilation in a contiguous room, of a sound reflector arranged outside the opening to reflect sound directed toward the opening away from the opening and a sound reflector arranged within the room adjacent the opening to reflect entering sound backward through the opening.

3. The combination with a wall having an 60

opening to provide ventilation in a contiguous room, of a sound reflector arranged outside the opening to reflect sound directed toward the opening away from the opening and a sound absorbing device arranged 70 within the room adjacent the opening to absorb a portion of the sound entering through the opening.

4. The combination with a wall having an opening to provide ventilation in a contiguous room, of a sound absorbing and reflecting device arranged within the room adjacent the opening to partially absorb and partially reflect back through the opening, sound entering through the opening. 75

5. The combination with a wall having an opening to provide ventilation in a contiguous room, of a sound absorbing device arranged outside the opening to reduce the volume of sound passing through the opening, and a sound absorbing device arranged within the room adjacent the opening to reduce the volume of the entered sound. 85

6. The combination with a wall having an opening to provide ventilation in a contiguous room, of a sound reflecting device arranged outside the opening to intercept sound coming toward the opening, a sound reflecting device arranged within the room adjacent to and spaced from the opening to reflect entering sound backward through the opening and a third sound reflecting device arranged within the room and adjacent the opening to reflect sound which passes the second reflector back toward the opening. 90

7. In combination with a wall having an opening, a window frame arranged in the opening, a sash arranged in said frame adapted to be moved to open the window at the bottom, a sound shield spaced from and arranged in front of the lower part of the window and a body of sound deadening material interposed between the bottom of the frame and the bottom of the shield. 105

8. In combination with a wall having an opening, a window frame arranged in the opening adjacent the inner side thereof, a sash arranged in said frame adapted to be moved to open the window to provide ventilation, a sound shield disposed in the opening adjacent the outer side thereof and arranged to intercept sounds coming toward the opening in the window and a body of sound deadening material arranged in the path of sound which is not intercepted by the shield. 110

9. In combination with a wall having an opening, a window frame arranged in said opening, a sash arranged in said frame adapted to be moved to open the window to provide ventilation, a sound shield arranged outside the window to intercept sound coming toward the opening in the window, sound deadening material covering the upper surface of the opening in the wall and a 115 120 125 130

- sound shield arranged on the inside of the window to intercept sound coming through the opening in the window.
10. The combination with a wall having an opening to provide ventilation in a contiguous room, of a vertically movable sound deflector arranged in the room adjacent the opening and adapted to be moved from operative to inoperative position.
- 10 11. The combination with a wall having an opening to provide ventilation in a contiguous room, of a sound nullifying device arranged in the room adjacent the opening, comprising means forming a plurality of sound absorbing chambers of decreasing size inwardly.
12. The combination with a wall having an opening to provide ventilation in a contiguous room, of a frame arranged in the room adjacent the opening, a plurality of approaching vanes on said frame and sound deadening material covering said vanes.
- 20 13. The combination with a wall having an opening to provide ventilation in a contiguous room, of a box-like structure arranged in the room adjacent the opening, a plurality of walls in said structure, said walls approaching each other inwardly to provide gradually restricted chambers, and sound absorbing material lining said walls.
14. The combination with a wall having an opening to provide ventilation in a contiguous room, of a plurality of spaced walls forming sound pockets arranged in the room adjacent the opening, said pockets being so disposed that sound reflected from them is directed outward through the opening.
- 30 15. A sound nullifying device comprising a series of vanes lined with sound absorbing material so arranged with relation to each other as to cause a plurality of reflections of sound and maximum absorption of sound in a minimum space.
- 40 16. The combination with a wall having an opening therein to provide ventilation in a contiguous room, of a concave reflector ar-
- ranged within the room adjacent the opening and positioned to reflect back through the opening a beam of the sound waves which enter through the opening and strike the reflector.
17. In combination with a wall having an opening, a window frame arranged in said opening, a sash in said frame adapted to be raised to open the window at the bottom to provide ventilation and a sound deflector arranged on the inside of the window at the base thereof, the bottom of the deflector being spaced from the bottom of the sash to provide an upwardly opening ventilating passage between the deflector and the sash and the deflector being arranged to deflect outwardly through the opening, sound which enters through the opening.
18. The combination with a wall having an opening, a window frame arranged in said opening, and a sash arranged in said frame adapted to be moved to open the window, of a sound deflector arranged outside the window to deflect sound directed toward the window opening and a sound deflector arranged inside the window with the bottom thereof spaced from the bottom of the sash to permit maximum ventilation through the window opening and the top thereof being spaced from the plane of the sash a distance not greater than the spacing of the bottom from the plane of the sash, whereby the maximum amount of sound is reflected back through the opening.
- 70 19. A sound minimizing ventilator adapted to be applied to an opening in the wall of a room comprising means for absorbing a portion of the sound waves tending to enter said opening, and a transparent shield for reflecting the unabsorbed sound waves in a direction to prevent their entrance into the room.
- In testimony whereof, I have hereunto set my hand.

JOHN F. NEWSOM.
